UNITED STATES PATENT OFFICE.

ALBERT THOMAS McILVAIN AND GEORGE FREDERICK STOVER, OF OLATHE, KANSAS.

COMPOUND FOR RENDERING PHOTOGRAPHS TRANSLUCENT.

No. 902,102.

Specification of Letters Patent.

Patented Oct. 27, 1908.

Application filed January 26, 1907. Serial No. 354,243.

To all whom it may concern:

Be it known that we, ALBERT T. McILVAIN and GEORGE F. STOVER, citizens of the United States, residing at Olathe, in the county of Johnson and State of Kansas, have invented a new and useful Compound for Rendering Photographs Translucent; and we do hereby declare the following to be a full, clear, and exact description of the invention, such as will enable others skilled in the art to which it appertains to make and use the same.

This invention relates to improvements in the art of rendering photographs and other pictures transparent and consists in the combination of certain elements hereinafter described.

It is often desirable to employ photographs of objects persons or scenes for hand painting, but it is difficult to produce a thoroughly artistic product when using an ordinary photograph.

By means of this invention, it is possible to produce a first class painting on a window or other substance of like nature. If it be desired to ornament a window with a scenic effect, a suitable photograph is secured and the following compound is applied thereon:

one ounce of balsam of fir, one ounce of poppy oil, half an ounce of spirits of turpentine, six drops of fluid extract of alkanet root. The effect of this preparation is to give the photograph a very desirable transparency, such as could not be secured heretofore. When the photograph is dried it is then in condition to receive the various colors for transforming it into a painting.

In the preparation of the above invention it is desirable to first mix the balsam of fir, the poppy oil and the spirits of turpentine, before adding the alkanet extract.

What we claim and desire to secure by Letters-Patent is:

The process of rendering photographs transparent consisting in applying to photographic prints a compound prepared of balsam of fir, poppy oil, spirits of turpentine and alkanet root extract.

In testimony whereof we have signed our names to this specification in the presence of two subscribing witnesses.

ALBERT THOMAS McILVAIN.
GEORGE FREDERICK STOVER.
